Specification for Design.

Patented Oct. 11, 1921.

Application filed May 3, 1921. Serial No. 466,624. Term of patent 14 years.

To all whom it may concern:

Be it known that I, DONALD L. BENTON, a citizen of the United States, residing at Adrian, in the State of Michigan, have invented a new, original, and ornamental Design for Automobile-Buffers, of which the following is a specification, reference being had to the accompanying drawing, forming a part thereof.

The figure is a perspective view of an automobile buffer showing my new design.

I claim:

The ornamental design for an automobile buffer as shown.

In testimony whereof, I have signed this specification.

DONALD L. BENTON.
